UNITED STATES PATENT OFFICE

ROBERT F. McCARTHY, OF WEBSTER GROVES, MISSOURI, ASSIGNOR TO INTERNATIONAL SHOE COMPANY, OF ST. LOUIS, MISSOURI, A CORPORATION OF DELAWARE

SHOE

Application filed April 3, 1929. Serial No. 352,146.

This invention relates to shoes and has special reference to elastic bodies secured between the counter and the lining near the rear portion of the shoe upper and forming 5 fillers to fit more closely against the sides of the foot of the wearer so as to prevent the shoe from slipping.

Specifically the present invention comprises improvements in the construction, arrangement and relationship of parts comprising the subject matter of my prior application for patent for shoe, filed December 24, 1928, Serial No. 328,211; and an object 10 of this present invention is to provide improved means for locating and supporting the elastic bodies in proper positions in connection with the shoe lining so that when the lining is attached to the outer portion of the upper all of the parts will be properly located and positioned and permanently supported.

Another object of the invention is to provide a shoe embodying the new and useful subject matter and obtaining all of the 15 advantageous results herein made apparent, reference being made to the drawing in which,

Fig. 1 is a perspective view of a shoe embodying the present invention.

Fig. 2 is a cross sectional view of the rear 20 portion of the shoe showing the elastic bodies in position between the lining and the counter.

Fig. 3 is a perspective view of the inside 25 of the rear portion of the shoe upper before being shaped upon the counter showing the swells or enlargements formed by the elastic bodies confined between the lining and the outer portion of the shoe.

Fig. 4 is a view showing the elastic bodies 30 attached to the lining, a fragment of the outer portion of the upper in connection with the lining also being shown turned away from the lining.

Fig. 5 is an inner side elevation of one of 35 the elastic bodies.

Fig. 6 is a side edge view.

Fig. 7 is an upper end or edge view.

The shoe from which the present invention 40 is shown is of the low type, the heel portion comprising an upper 1, a counter 2 of comparatively stiff material, and a lining 3. My

present invention comprises elastic bodies 4 of soft rubber or equivalent material having upwardly extended tongues 5. These bodies 4 are secured between the counter 2 and the lining 3 so that their convexed inner surfaces 55 cause the lining to form similarly convexed extended portions 6 arranged in such relationship that they extend into the cavities at the sides of the tendons below and rearwardly of the ankle joint and above the sole of the 60 heel of the foot of the wearer. These bodies 4 are preferably adhesively secured to the lining 3, proper location being assured by providing defined points upon the lining to guide and direct the operator in applying the bodies 65 4 thereto. In the construction and arrangement shown I have provided notches 7 in the upper edges of the lining 3, which notches 7 constitute defined parts or points across which the tongues 5 are located with the 70 upper ends of said tongues even or flush with the upper edge of the lining. When the bodies 4 are thus located with the tongues 5 across the defined points or parts 7 and even with the upper edges of the lining the bodies 75 4 are essentially and unvaryingly located in proper position. As stated, these bodies 4 and their tongues 5 may be and preferably are secured to the lining 3 by some adhesive substance so that they will not become displaced during further work in the construction 80 of the shoe. After the bodies 4 have been thus located the upper edge of the lining 1 is secured to the upper edge of the outer portion of the shoe upper by a row of stitches 8 85 running near and parallel with the upper edges of said parts and crossing the tongues 5.

The distance transversely between the surfaces 6 is considerably less than the distance 90 transversely between the surfaces of the lining below and about said surfaces 6 so that the broad portion of the heel of the foot of the wearer comes below the surfaces 6 which fit within the cavities above the broad heel 95 portions of the foot. Since the bodies 4 are of soft rubber or equivalent material they will not cause discomfort but will hold the shoe more perfectly fitted on the foot and prevent the shoe from slipping from the foot of the 100

wearer or the foot of the wearer from slipping from the shoe.

I have found by practical experience that by the present invention I am enabled to locate the parts more rapidly and accurately and to make the shoes with greater rapidity and at lower cost. Thus, I obtain many desirable advantages.

The construction and arrangement may be varied within equivalent limits without departure from the nature and principle of the invention.

What I claim and desire to secure by Letters Patent is:—

1. A shoe comprising a shoe lining having a defined point therein, an elastic body attached to the outer side of the lining in a definite relationship to said defined point, a shoe upper having its upper edge secured to the lining, and a counter secured between the upper and the lining at the heel portion of the shoe and at the outer side of said body.

2. A shoe comprising a shoe upper, a lining having its upper edge secured to the shoe upper and having defined points on its outer side, elastic bodies having convex inner surfaces attached to the outer side of said lining in a definite relationship to said defined points, tongues on said bodies extending across said defined points, and a counter secured between the shoe upper and the lining against the outer sides of said bodies.

3. A shoe comprising a shoe upper, a counter secured within the upper at the heel portion of the shoe, a lining secured to the inside of the shoe, a pair of spaced elastic bodies secured to said lining, tongues on said bodies, and stitches securing the lining and the shoe upper together and attaching said tongues to said lining and said upper.

ROBERT F. McCARTHY.
